UNITED STATES PATENT OFFICE.

AXEL W. CARLSON, OF WORCESTER, MASSACHUSETTS, ASSIGNOR TO CARLING TURBINE BLOWER CO., OF WORCESTER, MASSACHUSETTS, A CORPORATION OF MASSACHUSETTS.

TURBINE-BLOWER.

1,307,111.

Specification of Letters Patent. Patented June 17, 1919.

Application filed May 27, 1918. Serial No. 236,810.

To all whom it may concern:

Be it known that I, AXEL W. CARLSON, a citizen of the United States, residing at Worcester, in the county of Worcester and 5 State of Massachusetts, have invented a new and useful Turbine-Blower, of which the following is a specification.

This invention relates to a turbine blower of the steam operated type, it being understood that compressed air or other fluid under pressure may be substituted for steam as the operating medium.

It is the general object of my invention to improve the construction of such blowers, 15 rendering them safer and more efficient in operation, more flexible in control, and more convenient in adjustment.

With this general object in view, an important feature of my invention relates to 20 the provision of an improved type of fan casing or air tube which, in the preferred form, comprises a substantially cylindrical intermediate portion adjacent the fan blades, combined with enlarged entrance and discharge portions positioned at each end thereof. By this improved construction the efficiency of the fan is much improved and a 25 substantially noiseless operation is made possible.

Another feature of my invention relates to 30 an absolutely effective emergency stopping device dependent for its operation upon the radial expansion of the rotary driving member or rotor when the speed rises materially above the normal speed. This stopping device is positive in its operation and cannot become disarranged.

An additional feature of my invention relates to an improved construction of casing 40 for a turbine, so designed that the delivery of steam or other fluid under pressure to the movable vanes is facilitated, and flexible control is conveniently obtained. By placing the distribution passages, nozzles, 45 and control valves upon the removable cover portion of the casing, the working parts of the turbine are most conveniently accessible for inspection or repairs when the cover is removed.

Further features of my invention relate 50 to an improved type of bearing for the turbine shaft, to an improved form of centrifugal governor for the turbine, and to an improved type of valve for controlling each 5 separate nozzle.

My invention also relates to arrangements and combinations of parts hereinafter described and more particularly pointed out in the appended claims.

A preferred form of my invention is 60 shown in the drawings, in which—

Figure 1 is a longitudinal sectional elevation of my improved turbine blower;

Fig. 2 is a detail side elevation of a portion of the casing cover;

Fig. 3 is a plan view of the parts shown in Fig. 2;

Fig. 4 is a sectional elevation taken along the line 4—4 in Fig. 2, and showing my improved valve construction;

Fig. 5 is an enlarged detail sectional elevation, showing the construction of the fixed and movable vanes and their supporting parts;

Fig. 6 is a sectional detail plan view taken 75 along the line 6—6 in Fig. 5, and

Fig. 7 is a detail sectional elevation taken along the line 7—7 in Fig. 1, and showing the construction of the centrifugal governor.

Referring to the drawings, I have shown a 80 casing 10, (Fig. 1) having a cover portion 11 secured thereto, said casing and cover supporting the bearings for a main shaft 12 upon which the rotary driving member or rotor 13 is mounted. A fan 14 is also secured to the main shaft 12 and rotates within a fan casing 15.

This fan casing is of special construction and includes a substantially cylindrical intermediate portion 15^a, an enlarged or bell-shaped entrance portion 15^b, and a cone-shaped discharge portion 15^c. The cylindrical portion 15^a is of such diameter that it just clears the ends of the fan blades. This portion is preferably located as shown 95 in Fig. 1, beginning at a point substantially midway between the edges of the fan blades and extending to the edges of the blades on the discharge side. The provision of a fan casing of this particular design is found to 100 largely increase the efficiency of the blower, and also to greatly reduce the noise when the blower is in operation.

The shaft 12 extends through glands or stuffing boxes 16 in the inside of the casing, 105 and is rotatable on ball bearings 17 and 18 located near the opposite ends of the shaft.

These bearings are of special construction, and will now be described, reference being made particularly to the bearing 17. An 110

oil chamber 19 is formed adjacent the bearing 17 within a sleeve 20, said chamber being fed from a suitable oil cup 21. In order to prevent the escape of oil along the shaft 5 in either direction, I provide packing rings 22 which are held in position by collars or followers 23. These collars are forced against the packing to compress the same by spring disks 24 drawn against the opposite 10 ends of the bearing by screws 25. By turning the screws 25, the spring disks or plates 24 may be caused to force the collars 23 against the packing rings 22 to thereby compress the rings to any desired extent, thus 15 forming an oil-tight joint around the rotating shaft.

The driving member 13 is shown herein as having two sets of movable vanes 30 and 31 mounted thereon and spaced about its 20 periphery. The use of two sets of vanes is not always essential, and many features of my invention may be utilized in a turbine having only a single set of movable vanes. Where two sets of movable vanes are used, I 25 provide also a third partial set of fixed vanes 32 extending a certain distance around the inside of the casing 10 and fixed in a segmental band 33 (Fig. 5) which is secured to the casing 10 by screws 34. The fixed vanes 30 32 are of course mounted in that portion of the casing which is adjacent the nozzles. The different sets of vanes may be secured 35 to their supporting structures in any convenient manner, and I have herein indicated each vane as provided with a lug at each end, one lug on each vane being received in the supporting structure and the other lug being riveted or otherwise secured in bands or rings 35, 36 and 37 (Fig. 5).

40 A flange 38 (Fig. 1) is formed on the inside of the casing cover 11, said flange being of the same radial curvature as the segmental band 33 and forming a continuation thereof. The flange 38 and band 33 are concentric with the ring 35 in which the outer 45 ends of the vanes 30 are secured, and the clearance outside of the ring 35 is so small that the ring will frictionally engage the band and flange if it is radially enlarged to 50 a slight extent by centrifugal force due to excessive speed. The friction caused by such engagement will immediately decrease the speed, and the device is thus effective to prevent destruction of the turbine, in case the 55 fan becomes detached from the main shaft. The clearance is so small that the parts will frictionally engage before the rotor has expanded beyond its elastic limit.

I have also provided a centrifugal governor 60 nor which will commonly operate to shut off the steam or other fluid before the rotor expands sufficiently to engage the flange 38. This governor is of special construction, as shown in Figs. 1 and 7, and comprises 65 weighted arms 40 pivoted at 41 to a casting

42 fixed to the shaft 12. The arms 40 have inwardly extending portions 43 adapted to engage a flanged collar 44 slidable on the shaft and forced against the arms by a heavy spring 45. As the speed increases the weighted arms 40 move outward, compressing the spring 45, and the ends of the arms finally engage a resilient band 46 (Fig. 7) mounted concentric with the shaft 12 and having one end secured to a fixed pivot 47. The opposite end 48 of the band 46 is free to move outward and upward when engaged by the weighted arms 40. Such movement of the end 48 is effective through a link 49, bell crank 50 (Fig. 1), and link 51 to close the 70 main valve 52 (Fig. 2) by which steam or other fluid is admitted to the turbine.

This device is not intended primarily for a speed regulator, but rather for a safety device to stop the rotor if the speed becomes 75 excessive. If this governor fails to act, the speed will then be controlled and limited by the friction flange, as above described.

In Figs. 2, 3 and 4 I have shown the passages and connections through which steam or other fluid is admitted to the turbine. These passages are preferably formed in the casing cover 11. Steam is admitted to the main passage 53 when the valve 52 is open, said passage 53 being connected by a cross 80 passage 54 (Fig. 2) to an inclined passage 55 in which the first nozzle is located. Secondary passages 56 (Figs. 3 and 4) are provided adjacent the main passage 53 and steam may be admitted to these secondary 85 passages by opening valves 57. These secondary passages are connected to additional inclined passages 58 in which the second and third nozzles are mounted. With this construction the turbine may be driven by the 90 first nozzle alone, or by two or three nozzles as required by the load.

The valve 57 is of special construction, as best shown in Fig. 4, the valve having a valve stem 60 to which a head 61 is secured 95 and said head having opposed beveled faces. When the valve is closed, one beveled face of the head 61 engages a seat and closes the opening between the main passage 53 and the secondary passage 56. When the valve 100 is fully open, the opposite beveled face of the head engages a seat in the valve casing, and prevents escape of steam around the valve stem. As the steam employed in turbines of this type is frequently of very high 105 pressure, this construction is found very advantageous.

It will be noted that the nozzles, controlling valves, and steam passages are all 110 formed in or mounted on the casing cover and may be removed as a unit therewith. This construction permits very ready access 115 to the rotary member 13 in case inspection or repairs are necessary.

It will be evident from the foregoing de- 120

scription that I have provided a turbine blower having many and important novel features, the whole design resulting in greatly increased safety and efficiency.

Having thus described my invention, it will be also evident that changes and modifications can be made therein by those skilled in the art without departing from the spirit and scope thereof as set forth in the claims, and I do not wish to be otherwise limited to the details herein disclosed, but what I claim is—

1. In a turbine blower, a rotary driving member, and an emergency stopping device effective to frictionally engage said member if the latter expands under centrifugal force at excessive speed.

2. In a turbine blower, a rotary driving member, and an emergency stopping device

surrounding said member, said device being 20 closely concentric with said member and frictionally engaging the outer edge surface of said member when said member expands under centrifugal force at excessive speed.

3. In a turbine blower, a casing, a rotary 25 driving member therein comprising a disk, a series of vanes spaced around the periphery of said disk, a ring surrounding said vanes and in which their outer ends are secured, and devices fixed to said casing and 30 positioned closely concentric with said ring, said devices being effective to stop said member if the member expands under centrifugal force at excessive speed.

In testimony whereof I have hereunto 35 affixed my signature.

AXEL W. CARLSON.
